Inventor,
Abner H. Bennett.

UNITED STATES PATENT OFFICE.

ABNER HILL BENNETT, OF DECATUR, TENNESSEE, ASSIGNOR OF ONE-HALF
TO JESSE H. GUINN, OF SAME PLACE.

PLOW.

SPECIFICATION forming part of Letters Patent No. 391,576, dated October 23, 1888.

Application filed May 22, 1888. Serial No. 274,691. (No model.)

To all whom it may concern:

Be it known that I, ABNER HILL BENNETT, a citizen of the United States, residing at Decatur, in the county of Meigs and State of Tennessee, have invented new and useful Improvements in Plows, of which the following is a specification.

The invention relates to improvements in plows; and it consists in the construction and novel combination of parts hereinafter described, illustrated in the drawings, and pointed out in the claim.

In the drawings, Figure 1 is a perspective view of a plow embodying the invention. Fig. 2 is a plan view of the same with the handles detached. Fig. 3 is a perspective view of the shorter and adjustable plow-beam detached.

Referring to the drawings by letter, A designates the main plow-beam, composed of the front wooden part, B, having the opposite transverse shoulders *b b* across its rear portion, and the deeper transverse shoulders *b' b'* near its rear end, and the metal part C, composed of the curved standard *c* at its rear, the solid portion *c'* adjoining the said standard, and the front portion, *c''*, composed of the upper and lower plates *c' c''*, the front parts of which are bent to conform to the shoulders *b b'*. The said plates are connected to the wooden part by vertical bolts and nuts, as shown, with their ends flush with the upper and lower surfaces thereof.

D D are the handles connected, as usual, below their upper ends by a bar, and with their lower ends bound tightly together by bolts that pass through them and the side plates, *d d*. The said plates lie against the outer side of the handle and the sides of the solid metal portion *c'* of the plow-beam, to which they are bolted firmly, their ends being bent under and against the plow-beam.

The metal plates *c''* are provided with the series of registering openings *e e*, as shown, to receive the vertical adjusting-pin *E*.

F is the shorter adjustable plow-beam, which is of metal and has its rear portion formed into the curved standard *f*, similar to the standard

c of the main beam, and its front end, *f'*, bent at right angles inward, and reduced in thickness to pass snugly between the plates *c'*. The 50 said end has a perforation which can be made to register with any one of the pairs of openings *e*, and held thereto by the pin *E*.

The standards *c* and *f* have secured to them similar blades or shares *G G'*, respectively. 55

H is a link-plate provided with an elongated longitudinal slot, *h*, and pivoted at one end upon the main plow-beam, just in rear of the handles, and I is a bolt-rod rising vertically from a proper point of the adjustable plow-beam. 60 The said bolt-rod passes through the slot *h*, and is engaged thereabove by a nut, *i*, below which is an ordinary metal washer.

It is obvious that by means of the openings *e* and pin *E* the beam *F* can be adjusted longitudinally with reference to the main beam, and by means of the slotted link, bolt, rod, and nut the adjustable beam can be set at different angles on the main beam. Thus the share *G* can be set immediately behind the share *G* to 65 deepen the furrow in subsoil plowing, or it can be set opposite thereto to cover rows of corn, or may be behind, and with its beam forming an angle with the main beam. 7c

If desired, the adjustable beam may be detached, and the machine used as a single plow. 75

Having described my invention, I claim—

In a plow, the combination, with the main beam and the standard at the rear end thereof, of the shorter plow-beam adjustable both longitudinally and angularly with relation to the main beam, and the standard at the rear end of the shorter beam, which, by means of said shorter beam, can be set either in rear of the main-beam standard or opposite to and on one 80 side thereof, substantially as specified. 85

In testimony that I claim the foregoing as my own I have hereto affixed my signature in presence of two witnesses.

ABNER HILL BENNETT.

Witnesses:

I. C. ARRANTS,
I. B. BRANDON.
